UNITED STATES PATENT OFFICE.

JOSEPH H. FULMER, OF NAZARETH, PENNSYLVANIA.

SNOW-GUARD FOR ROOFS.

No. 817,480.

Specification of Letters Patent.

Patented April 10, 1906.

Application filed July 21, 1905. Serial No. 270,728.

To all whom it may concern:

Be it known that I, JOSEPH H. FULMER, a citizen of the United States, residing at Nazareth, in the county of Northampton and State of Pennsylvania, have invented a new and useful Snow-Guard for Roofs, of which the following is a specification.

This invention relates to means for preventing snow and ice in large cakes from sliding off of pitched roofs, and has for its object to provide an improved device of this character which is capable of being conveniently secured to the roof without damage to the shingles thereof and which will be inexpensive, durable, and highly efficient for the purpose designed.

The invention consists in the combination and arrangement of parts, as will be herein-after more fully described, shown in the accompanying drawings, and particularly pointed out in the appended claim, it being understood that changes in form, proportion, size, and minor details may be made within the scope of the claim without departing from the spirit or sacrificing any of the advantages of the invention.

In the accompanying drawings, Figure 1 is a detail sectional view of a portion of a roof having the snow-guard of the present invention applied thereto. Fig. 2 is a detail perspective view of the snow-guard.

Like characters of reference designate corresponding parts in both figures of the drawings.

As embodied in Fig. 2 of the accompanying drawings, it will be seen that the present device is formed from a single length of heavy wire which is first bent intermediate of its ends into a loop 1, the opposite wire portions then being tightly intertwisted to form a rigid stem 2, from which the opposite portions of the wire are extended in opposite directions in a plane at substantially right angles to that of the loop 1, so as to form a relatively long shank 3 and a shorter brace member 4, the outer extremity of the shank being bent to form a prong 5, which is pointed at its outer terminal.

In practice the shank and brace of the guard are placed upon the upper portion of a shingle 6, which has been previously connected to the sheathing or other portion 7 of the roof with the shank extending above the upper edge of the shingle and the prong driven into the sheathing. After the device has thus been fitted in place the next above shingle is fitted in place over the top of the shank and overlapping the upper edge portion of the shingle 6 in the usual manner, whereby the guard is secured by the upper shingle in addition to the fastening afforded by the prong 5. When thus applied, the loop 1 constitutes a guard-shoulder for the support of such snow and ice as may be accumulated against the upper face of the loop, whereby such accumulation will be held against sliding off of the roof in a comparatively large mass. The lower end portion 4 of the wire constitutes a brace to prevent bending of the loop, and the latter is furthermore stiffened by the twisted stem portion 2, whereby the device is rendered exceedingly strong and durable without requiring any extraneous bracing means or otherwise complicating the device.

Having thus described the invention, what is claimed is—

A snow-guard consisting of a shank terminating at one end in a laterally-directed fastening-prong and having an intermediate portion of the shank twisted upon itself to form a rigid stem disposed at substantially right angles to the shank and terminating at its outer end in a loop set transversely of the shank, the stem and the loop being upon one side of the shank, and the prong upon the other side of the shank.

In testimony that I claim the foregoing as my own I have hereto affixed my signature in the presence of two witnesses.

JOSEPH H. FULMER.
